[57] CLAIM

The ornamental design for a child's booster seat, as shown and described.

DESCRIPTION

FIG. 1 is a perspective view of a child's booster seat showing our new design with the base thereof in right

side up orientation to place the child's booster seat in an elevated position and the shield thereof in a use position; FIG. 2 is a front elevational view showing the child's booster seat in the elevated position; FIG. 3 is a left side elevational view showing the child's booster seat in the elevated position; FIG. 4 is a right side elevational view showing the child's booster seat in the elevated position; FIG. 5 is a rear elevational view showing the child's booster seat in the elevated position; FIG. 6 is a top plan view showing the child's booster seat in the elevated position; FIG. 7 is a bottom plan view showing the child's booster seat in the elevated position; FIG. 8 is a perspective view showing the shield of the child's booster seat placed in a position to permit ingress to and egress from the booster seat; FIG. 9 is a left side elevational view showing the base thereof in an upside-down orientation to place the child's booster seat in a non-elevated position; FIG. 10 is a front elevational view showing the child's booster seat in a non-elevated position; FIG. 11 is a right side elevational view showing the child's booster seat in a non-elevated position; FIG. 12 is a front elevational view showing the child's booster seat in a non-elevated position; FIG. 13 is a bottom plan view showing the child's booster seat in a non-elevated position.
